(57) **CLAIM**

The ornamental design for a handle for a machine, as shown and described.

DESCRIPTION

FIG. 1 is a front perspective view of a handle for a machine, showing our new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The phantom dashed lines of FIGS. 1–6 showing the buttons, roller, and mounting hardware are for illustrative purposes only and form no part of the claimed design relative to the particular embodiment shown.
